UNITED STATES PATENT OFFICE.

GEORGE A. WOODMAN, OF CHICAGO, ILLINOIS.

JOURNAL-BOX LID.

Application filed April 1, 1918. Serial No. 225,891.

My invention relates to journal-box lids primarily intended for use in connection with railway car journal boxes.

One of the principal objects of my invention is the provision of a lid which, while securely held in closed position to exclude foreign matter from the journal box, may be readily opened when necessary to obtain access to the box.

10 Further objects of my invention are the provision of a simple and relatively inexpensive structure which operates without binding and which, thoroughly seals the opening in the journal box.

15 Further objects and advantages of my invention reside in the various combinations hereinafter described as will be apparent as it is better understood by reference to the following specification when read in connection with the accompanying drawing, illustrating the preferred embodiment thereof, in which

Fig. 1 is a vertical section through the lid and a portion of the journal box;

25 Fig. 2 is a front elevation of the follower;

Fig. 3 is a side elevation of the follower, and

Fig. 4 is a section illustrating a slightly different form of my invention.

30 Referring to the drawing, 5 indicates a journal box which may be of any preferred or usual form and construction. The journal box is provided with the usual opening permitting access to the interior thereof, 35 which is normally closed by a lid 6, pivotally supported on a pintle 7, mounted in a lug 8 on the upper wall of the journal box.

The lid 6 is provided with a housing 9 to receive a coiled spring 10 and a follower 11, 40 which is held in engagement with the face of the lug 8 by the spring. The follower 11 is provided with wings 12 at its sides and a notch 13 at its top. The wings 12 rest on the fins 14, formed on the interior face of the housing 9. A fin 15 is also formed on the interior face of the housing at the top thereof and engages the notch 13. The follower 11 is thus supported on the fins 14 and guided at the top by the fin 15, and I have 45 found that this structure provides guiding means for insuring rectilinear movement of the follower towards and away from the lug 7 and thereby prevents binding of the follower as it moves within the housing during 50 the operation of opening or closing the lid. The lid 6 is provided with spaced lips

16, adjacent its edges to embrace both sides of the edges of the opening in the journal box 5. The lips 16 thoroughly seal the opening and prevent the entrance of dust or 60 other foreign matter.

The front face 17 of the lug 8 is formed to provide a convex, cylindrical surface portion eccentric to the pivotal axis of the lid, and the co-operating face of the follower 11 65 is preferably provided with a concave, cylindrical surface conforming substantially to the surface 17. Preferably, the convex surface 17 merges near its bottom into the rounded shoulder 18 and at its top into the rounded shoulder 19. The concave surface of the follower 11 preferably merges into the shoulder 20, which, when the lid is closed underlies the shoulder 18 and assists in locking the lid in closed position. I have found that by providing an eccentric convex, cylindrical surface on the lug 8, the operation of opening and closing the lid is materially facilitated without destroying the effectiveness of the follower and spring as a means 80 for holding the lid in closed position.

In Figure 4 of the drawing, I have illustrated a slightly different form of my invention in which the upper front face of the lug 8 is provided, at 21, with an eccentric convex, cylindrical surface portion which merges downwardly into a flat surface 22, having a shoulder 24 at its lower end. The co-operating surfaces of the follower 11 are 85 preferably made to conform substantially to the surfaces 21 and 22, and a shoulder 25 underlies the shoulder 24 when the lid is 90 in closed position. The remaining parts of the structure are the same as those previously described in connection with Figure 1 95 and are correspondingly numbered in the drawing.

The operation of the structure will be 100 readily understood from the following brief description thereof. When the lid is in closed position, the parts are disposed as indicated in Figures 1 and 4, and the lid is firmly locked. When, however, force is applied to the lid, the follower 11 is caused to slide over the eccentric convex, cylindrical face, the spring 10 being thereby compressed, until the follower passes over the shoulder 19 in Figure 1 or the upper portion of the cylindrical face 21 in Figure 4. In 105 this position the spring 10 is permitted to expand and thus holds the lid firmly in raised position.

From the foregoing, it will be readily understood that I have perfected a journal-box lid which is normally held in closed position and which may be moved with a minimum of effort to open position to permit access to the box. My invention overcomes a disadvantage in similar constructions having flat co-operating faces on the lug and follower, it being necessary with such structures to exert a considerable force on the lid before it can be opened. The manner of supporting and guiding the follower is important because the follower is prevented thereby from binding in the housing during the operation of the lid. The lips which embrace the edges of the opening in the journal-box securely seal the box when the lid is in closed position.

Various changes may be made in the form, construction, and arrangement of the parts without departing from the spirit and scope of the invention or sacrificing any of its material advantages, the forms hereinbefore described being merely preferred embodiments thereof.

I claim:

1. A journal box having an upstanding lug, a lid pivotally mounted on said lug and provided with a housing, the front face of the lug having an intermediate convex portion eccentric to the pivotal axis of the lid, a bodily movable follower slidably mounted in the housing and guided for rectilinear movement towards and away from the lug, and a spring yieldably maintaining the follower in frictional engagement with the lug, the follower having a contact face portion conforming to the convex portion of the lug for facilitating the operation of the lid for opening and closing the lid.
2. A journal box having an upstanding lug, a lid pivotally mounted on said lug and provided with a housing, the front face of the lug having an intermediate convex portion eccentric to the pivotal axis of the lid and terminating in a lower shoulder, a bod-

ily movable follower slidably mounted in the housing and guided for rectilinear movement towards and away from the lug, and a spring yieldably maintaining the follower in frictional engagement with the lug, the follower having a contact face portion conforming to the convex portion of the lug for facilitating the operation of opening and closing the lid, said contact face of the follower having a lower shoulder underlying the shoulder of the lug in the closed position of the lid to hold the lid closed.

3. A journal box having an upstanding lug, a lid pivotally mounted on said lug and provided with a housing, the front face of the lug having an intermediate convex portion eccentric to the pivotal axis of the lid and terminating in upper and lower shoulders, a bodily movable follower slidably mounted in the housing and guided for rectilinear movement towards and away from the lug, and a spring yieldably maintaining the follower in frictional engagement with the lug, the follower having a contact face portion conforming to the convex portion of the lug for facilitating the operation of opening and closing the lid, said contact face of the follower having a lower shoulder underlying the shoulder of the lug in the closed position of the lid to hold the lid closed.

4. A journal box having an upstanding lug, a lid pivotally mounted on said lug and provided with the housing, a bodily movable follower slidably mounted in the housing and having a contact face portion in frictional engagement with the lug, there being a slidably supporting engagement between the upright sides of the follower and the inner walls of the housing, the top of the housing having a depending fin, and the top of the follower having a guide notch receiving the fin.

GEORGE A. WOODMAN.
